UNITED STATES PATENT OFFICE

149,780

DESIGN FOR A JEWELRY COMPONENT

Louis Schorr, Brooklyn, N. Y.

Application February 24, 1947, Serial No. 137,114

Term of patent 7 years

(Cl. D45—1)

To all whom it may concern:

Be it known that I, Louis Schorr, a citizen of the United States of America, residing at Brooklyn, in the county of Kings and State of New York, have invented a new, original, and ornamental Design for a Jewelry Component, of which the following is a specification, reference being had to the accompanying drawing forming part thereof.

Fig. 1 is a perspective view of a jewelry component embodying my new design;

Fig. 2 is a side view and Fig. 3, a top plan view of the same.

I claim:

The ornamental design for a jewelry component, substantially as shown.

LOUIS SCHORR.
